UNITED STATES PATENT OFFICE.

GEORGE S. WITHAM, JR., OF HOOSICK FALLS, NEW YORK.

PULP-WOOD GRINDER.

1,057,791.

Specification of Letters Patent.

Patented Apr. 1, 1913.

Application filed June 12, 1912. Serial No. 703,262.

To all whom it may concern:

Be it known that I, GEORGE S. WITHAM, Jr., a citizen of the United States, residing in Hoosick Falls, in the county of Rensselaer 5 and State of New York, have invented certain new and useful Improvements in Pulp-Wood Grinders, of which the following is a specification.

This invention relates to machines of the kind commonly employed to grind wood or other fibrous material used in the manufacture of paper pulp. The most generally used machine of this class comprises a rotary grindstone against which the wood, 10 contained in pockets, is pressed by followers operated usually by hydraulic power. As the relatively large pieces of wood are ground the "mechanical wood-pulp", as it is called, falls into a pit from which it is 15 taken for further treatment. In these machines, however, as heretofore constructed, the walls of the pockets being of metal have necessarily been held out of contact with the stone and often the distance between the 20 periphery of the stone and the adjacent edges of the pocket walls has been so great that chips, segments and small pieces of 25 wood of various shapes and insufficiently ground have escaped the grinding operation and fallen into the pit with the properly 30 ground pulp. These objections to the machines have been to some extent remedied by adjusting the pockets relatively to the stone, but such adjustments are difficult and 35 are often neglected.

The primary object of my invention is to so improve the machine that the escape of improperly ground pieces is automatically prevented. I have invented a general way 40 of accomplishing this result and also a number of specific devices which may be employed for this purpose. The general way is to provide linings or gates for the pockets which, while permitting the ground material 45 to pass from the pockets, confine the unground material and prevent its escape to the pit. These linings or gates are pressed against the periphery of the stone and are of such material that they are themselves 50 ground away as the operation progresses. The linings or gates may be pressed against the stone by their own gravity, by hydraulic

means, by mechanically-operated feed mechanism, and in various other ways, some of which are illustrated in the drawings and 55 will be hereinafter described.

Generally in this class of machines, wood is supplied to the pockets in the form of logs or blocks. My improved machine may be fed in this way, but it is also adapted to 60 grind or regrind pulp-wood in various forms, residue from ground wood, sulfite, sulfate, soda pulp, edgings, planks, deal ends, slabs, cornstalks, jute, hemp, etc., and what are known as pulp-screenings, *i. e.*, 65 the rejections or wastes from screening processes.

In carrying out my invention with these general objects in view, I have provided a machine embodying the characteristics above 70 mentioned and which also contains some additional features, such as means for automatically feeding the material to be ground, means for preventing the regrinding of the material and means for relieving the friction often existing in this class of machines 75 between the material and the side walls of the pockets.

In the accompanying drawings, Figure 1 is a view partly in side elevation and partly 80 in section of a pulp-wood grinding machine embodying my improvements. Fig. 2 shows a vertical section thereof on the line 2—2 of Fig. 1. Fig. 3 shows a section of the same on the line 3—3 of Fig. 1. Fig. 4 85 shows a horizontal section on the line 4—4 of Fig. 2. Figs. 5, 6, and 7 show a modified form of the invention; Fig. 5 being a view partly in end elevation, partly in section on the line 5—5 of Fig. 6 and with parts broken 90 away to better illustrate other parts; Fig. 6 showing a section on the line 6—6 of Fig. 5; and Fig. 7 showing a section on the line 7—7 of Fig. 5. Figs. 8 and 9 show a further modification, Fig. 8 being a view of part 95 of the machine in side elevation and Fig. 9 showing a section on the line 9—9 of Fig. 8. Fig. 10 is a detail view in vertical section illustrating another way of embodying my improvements; and Fig. 11 shows a horizontal section on the line 11—11 of Fig. 10. Figs. 12 and 13 are perspective views showing how the members of the pocket lining 100 or gate may be connected. Fig. 14 is a view

partly in side elevation and partly in section showing how the material to be ground may be automatically fed to the pockets, and it also shows another way of arranging the lining or gate of the pocket. Fig. 15 is a detail view in vertical section showing a way of feeding the gates of the pocket by their own gravity. Fig. 16 shows a way of feeding or adjusting the gates by set screws.

10 As before explained, the machine is adapted to grind various materials for the purpose of producing mechanical wood pulp, but hereinafter this material will be often designated as pulp-wood.

15 Referring to Sheet 1 of the drawings, and particularly to Fig. 1, it will be observed that in general construction the machine is of well known type. The rotary grinder A is attached to a shaft A' mounted in bearings connected with a casing B which covers the grinder and which is attached to a bed plate C above the pit, as usual. The opposite side plates of the casing, as usual, are connected by what are known as bridge trees 20 D which are interposed between and are arranged on opposite sides of the pockets or wood boxes E. These, as shown in Figs. 1 to 4, are in general of the usual construction being provided with sliding front doors 25 E' and being adjustable radially toward and from the grinder in the usual way. Above the pockets are hydraulic cylinders F which operate the followers G in the usual way. Each follower is provided with a vertical 30 rod g connected with an indicator G' which shows the position of the follower in the pocket and indicates the amount of material still unground.

As heretofore explained, in this class of 35 machines it is not permissible to allow the walls of the pockets to bear against the grindstone as this will unduly wear the stone and destroy the pocket walls which are of metal, therefore it is common in this 40 class of machines for chips, segments and pieces of wood of various sizes to escape past the pocket walls and fall into the pit with the properly ground material, and it has not been feasible to grind screenings or 45 small pieces of pulp-wood owing to the fact that such material would escape in the manner before explained before being properly ground. In order to overcome these disadvantages in the old machines, I have provided gates or linings for the pockets which 50 are pressed against the periphery of the grinder and prevent the escape of unground material.

In Figs. 1 to 4, H indicate pieces of wood 55 which are placed inside the pocket beneath the follower G and in this instance such pieces of wood constitute linings for the pocket and also gates therefor. The gates or linings are placed in the pocket before 60 the material X is inserted and then the ma-

terial is supplied while the follower is in an elevated position. The lining H is preferably four-sided and may have its members connected before being placed in the pocket, or the different members may be inserted 70 separately in the manner indicated in Fig. 4, the joints, as illustrated in Fig. 4, being in this instance mitered. Preferably the walls of the pocket are formed with vertical ribs e against which the boards bear in order to 75 reduce friction. When the boards are thus inserted and the material to be ground is supplied to the pocket, the follower is pressed radially toward the grindstone and the grinding operation proceeds. The follower not only presses the material X 80 against the periphery of the stone, but also presses the boards H against the periphery thereof so that these are ground away correspondingly with the grinding away of the material X, thus no large pieces of material can escape and the properly ground pulp-wood is delivered to the pit, it being understood of course, that the gates or linings H are of material which can properly 85 be used in the manufacture of wood pulp.

As is customary in this class of machines, a plurality of pockets is preferably employed and in such machines it often occurs that some of the pulp instead of passing directly to the pit is carried forward from one pocket to another and reground or made finer, thus producing flour pulp in the pit and pulp of different grades which is objectionable. In order to prevent this I provide wipers I between the pockets which arrest any ground material tending to pass from one pocket to the other and cause it to be delivered sidewise from the machine to the pit. Preferably these wipers are arranged in the bridge-trees D and each, as shown, consists of a board i pressed radially toward the periphery of the stone by hydraulic means I', or otherwise. It will be understood that when the gates H or the 100 boards i have been worn away, they can be quickly replaced.

In order to extend the life of the gates or linings for the pockets, I may arrange to feed them independently of the feed of the material X. In Figs. 5, 6 and 7 I have shown means for this purpose. The boards H are arranged inside of the pockets as in Fig. 1, but are not acted on by the follower G. The pocket is provided with upright 110 guide bars J and the boards H are arranged between the guide bars and the walls of the pocket which latter is provided with openings in its sides to permit the ready insertion of the boards, all of which is clearly 115 illustrated in the drawings, these openings being located in the upper parts of the pocket as indicated at K in Fig. 5. The boards may be inserted when the follower is either in a depressed or an elevated posi- 120 125 130.

tion, but the material X is fed to the pocket when the follower is elevated. Such material may be fed by hand, as is usual, but I prefer to employ a feed hopper L provided with a worm feed L'. The walls of the pocket have openings m in them through which project toothed wheels M which are operated by gearing N and engage the boards H in such manner as to press or feed the boards toward the rotary grinder A, or to exert such a pressure on the boards as to hold them in close contact with the grinder and prevent the escape of unground material.

In the drawings I have shown feed wheels M operating on boards in two sides of the pocket, the boards on the other two sides may be fed in any suitable way, their own weight or gravity being often sufficient.

In Figs. 8 and 9 I have shown still another way of arranging the linings or gates in the pocket. In this case gravity alone is depended on for holding the boards in contact with the grindstone. In Fig. 8 the devices b are for the purpose of adjusting the pockets radially toward and from the stone. The walls of the pocket are provided with vertical ribs J similar to those shown in Figs. 5 and 6 for reducing friction and the pocket is provided with a swinging door O which may be secured firmly in place by locking devices O'. One of the boards may be inserted through an opening o in the pocket while the other three boards may be inserted through the front door. After they are thus inserted and the material X is supplied, the door O may be closed and locked and then the machine may operate in the usual way, the boards being fed either by their own gravity or by being pressed toward the stone by the follower, or in any other suitable way.

In Figs. 10 and 13 I have shown still another way of arranging the lining or gate. In this case I preferably use a rectangular frame P formed of strips of wood which may be mortised together in the manner indicated in Figs. 12 and 13 and preferably one side of the frame is connected with a holder Q which carries bolts Q' extending through parts q, q' of the frame between which are interposed springs R bearing against the part q and against pins r on the bolts, the arrangement being such that the springs press the holder Q toward the stone A and therefore holds the frame P in contact therewith. One side of the frame may be made in the form shown at the right hand side of Fig. 10 and a door R' of the shape shown may be employed. The part of the frame below the door may carry one or more bolts R² connecting it with the frame and these bolts may be adjusted when required.

In machines of this class the material to be ground is usually supplied to the pockets

through doors which slide vertically in guides. I have found that material may be automatically fed to the pockets, when the latter are suitably constructed, by appropriate feed mechanism.

In Fig. 14 I have shown constructions suitable for feeding either screenings, slivers, or other comparatively comminuted material, or for feeding logs or sticks of the usual kind and I have also shown the pockets equipped with linings, gates or guards made in accordance with my invention. The follower G is operated in the manner before described and may be raised above the mouth s of the hopper S containing a feed screw S'. The material may be delivered to the hopper S from pulp screens or in any other suitable way and fed into the pocket when the follower is in the raised position. Any suitable means may be employed for closing the mouth of the pocket after the follower has descended. The pocket may be lined or provided with gates like those before described, but in this instance the gate or lining H is arranged in a recess in one wall of the pocket and above the gate is a follower T connected with a rod T' operated by hydraulic apparatus T². The pressure exerted on the gate need not be as great as that exerted on the material X and in this way the life of the lining or gate may be prolonged. Sticks or logs of wood may be fed to the pockets in the manner indicated where U shows a hopper for holding the wood. The mechanism T, T', T² is similar to that just described. The pocket may be provided with a door E of the kind hereinbefore mentioned and the follower may carry a gate V so arranged that when the follower is raised the wood may fall into the pocket and when the follower descends the opening from the hopper to the pocket may be closed.

In Fig. 15 the boards H are fed to the stone A by their own weight or gravity, suitable guides being formed in the pocket walls to receive them.

In Fig. 16 I have shown still another construction in which the gates or guards H are arranged outside the pockets being held in place by guides W and pressed toward the stone A by means of set screws W' which may be from time to time operated.

It will thus be seen that my improvements may be applied in various ways to machines of the most approved type with but little modification thereof. In some forms of the invention where the linings or gates are pressed toward the stone simultaneously with the other material to be ground great uniformity is effected in the grinding operation. In some machines of this class the side pressure and friction are so great that the proper feeding of the material is not effected.

I find it most desirable to employ some means for positively feeding or pressing the

linings or gates toward the stone, but I have obtained good results where gravity alone is depended upon for this purpose.

Another desirable feature of my improvements is that by providing ribs or similar guides for the linings or gates friction is largely reduced and better results obtained.

I claim as my invention:

1. A pulp-wood grinding machine, comprising a rotary grinder, a pocket, a follower for pressing the material to be ground against the grinder, and a gate or guard for the pocket automatically moved toward the grinder held in close contact therewith throughout the grinding operation.

2. A pulp-wood grinding machine, comprising a rotary grinder, a pocket, a follower for pressing the material to be ground against the grinder, a gate or guard for the pocket, and means for automatically pressing the gate into close contact with the grinder throughout the grinding operation.

3. A pulp-wood grinding machine, comprising a rotary grinder, a pocket, a follower for pressing the material to be ground against the grinder, and a lining for the pocket automatically pressed into close contact with the grinder throughout the grinding operation.

30 4. A pulp-wood grinding machine, comprising a rotary grinder, a pocket, a follower for pressing the material to be ground against the grinder, a wooden lining for the pocket, and means for pressing the lining into close contact with the grinder throughout the grinding operation.

5. A pulp-wood grinding machine, comprising a rotary grinder, a pocket, a gate or guard for the pocket, and mechanism for simultaneously and automatically pressing the material to be ground and the gate against the grinder throughout the grinding operation.

45 6. A pulp-wood grinding machine, comprising a rotary grinder, a pocket provided with vertical guide ribs, a wooden gate or guard bearing against said ribs and held in close contact with the grinder, throughout the grinding operation, and a follower for pressing the material to be ground against the grinder.

50 7. A pulp-wood grinding machine, comprising a rotary grinder, a pocket, a follower for pressing the material to be ground

against the grinder, and a wiper outside the 55 pocket held in close grinding contact with the grinder during the grinding operation.

8. A pulp-wood grinding machine, comprising a rotary grinder, a series of pockets arranged radially with reference thereto, 60 means within the pockets for holding the material to be ground in contact with the grinder, and a wooden wiper interposed between two adjacent pockets and held in grinding contact with the grinder for preventing ground material from passing from one pocket to another.

9. A pulp-wood grinding machine, comprising a rotary grinder, a casing therefor, bridge trees connecting the opposite sides of 70 the casing and interposed between the pockets, and wipers arranged radially in the bridge trees and automatically pressed in close grinding contact with the grinder during the grinding operation.

75 10. A pulp-wood grinding machine, comprising a rotary grinder, a pocket, a follower for pressing the material to be ground against the grinder, a gate or guard of grindable material for the pocket, and 80 means operating independently of the follower for automatically pressing the gate or guard against the periphery of the grinder throughout the grinding operation.

11. A pulp-wood grinding machine, comprising a rotary grinder, a pocket, a follower for pressing the material to be ground against the grinder, a wooden gate for preventing the escape of unground material from the pocket, a hopper connected with 90 the pocket, and means for feeding material to be ground from the hopper to the pocket.

12. A pulp-wood grinding machine, comprising a rotary grinder, a pocket, a follower for pressing the material to be ground against the grinder, a wooden gate or guard for the pocket held in close contact with the grinder during the grinding operation for preventing the escape of unground material from the pocket, a hopper connected with 100 the pocket, and means for feeding material to be ground from the hopper to the pocket.

In testimony whereof, I have hereunto subscribed my name.
